UNITED STATES PATENT OFFICE.

WARREN A. CALDWELL, OF OSKALOOSA, IOWA.

SILO.

1,242,420.

Specification of Letters Patent.

Patented Oct. 9, 1917.

Application filed July 20, 1915. Serial No. 41,006.

To all whom it may concern:

Be it known that I, WARREN A. CALDWELL, a citizen of the United States, residing at Oskaloosa, in the county of Mahaska, 5 and State of Iowa, have invented certain new and useful Improvements in Silos, of which the following is a specification.

This invention has relation to silos and like structures and has for its object to provide 10 convenient means whereby a silo or like structure may be formed of reinforced concrete or any other suitable material and to provide the same with various new and useful features which hereinafter will be 15 more particularly described and claimed.

The invention consists of a silo or like structure embodying numerous slabs or staves of reinforced concrete or other suitable material having interlocking margins and 20 bound by means of hoops, rods or bands, whereby the wall of the structure is rendered substantial and practically imperious to moisture, the slabs or staves entering into the formation of the wall being of 25 varying dimensions as desired.

A further purpose of the invention is the provision of a silo or like structure embodying slabs or staves constructed to interlock at their edges and arranged to break joint 30 vertically and laterally, the vertical courses having their meeting ends interlocked in a manner to admit of the binding hoops, bands, or the like, engaging portions of adjacent staves or slabs.

The invention, furthermore, has for its object the provision of a stave or slab of such formation as to admit of its use in the 35 formation of silos of different sizes, the several slabs or staves making substantial 40 interlocking joints in any one of the different sizes of silos within given limits.

With these and other objects in view, which will readily appear as the nature of the invention is better understood, the same 45 consists in the improved construction and novel arrangement and combination of parts which will be hereinafter fully described and particularly claimed.

In the accompanying drawings has been 50 illustrated a simple and preferred form of the invention, it being, however, understood that no limitation is necessarily made to the precise structural details therein exhibited, but that changes, alterations and 55 modifications within the scope of the inven-

tion as claimed may be resorted to when desired.

Referring to the drawings.

Figure 1 is a view in elevation of a silo embodying the invention; 60

Fig. 2 is a view in elevation of a slab or stave;

Fig. 3 is an edge view of the slab or stave;

Fig. 4 is an end view of the stave;

Fig. 5 is an enlarged sectional view of a 65 portion of the silo or like structure.

Corresponding and like parts are referred to in the following description and indicated in all the views of the drawings by the same reference characters. 70

In accordance with this invention the silo or analogous structure is formed of a plurality of slabs or staves having the general form indicated most clearly in Fig. 2 with the exception that the staves forming the 75 top and bottom courses of the structure have their outer edges straight and each of such courses comprising long and short staves having an alternate arrangement which results in the formation of break joints, as indicated most clearly in Fig. 1.

Fig. 2 illustrates a slab or stave which is preferably formed of concrete but which may be constructed of any suitable material. 80 The stave is oblong and is reinforced by means of a stay 1 which consists of a metal rod or bar having a diagonal arrangement and terminating a short distance from the ends and outer edges of the stave. Opposite ends of the stave are similarly offset so that 85 when a number of staves are placed end to end they will match, as indicated most clearly in Fig. 1. One end of the stave is formed with transverse edge portions 2 and 3 which are out of line and separated by 90 means of an intermediate longitudinal portion or shoulder 4. The transverse edge portions 2 and 3 are approximately of like length. The intermediate longitudinal portion 4 is of a length corresponding to the 95 distance between the edge portions 2 and 3. The shoulder or offset 4 as well as portions of the edges 2 and 3 are formed with half round grooves designated respectively by the numerals 5, 6 and 7. These several grooves 100 preferably extend the full thickness of the stave, as indicated most clearly by the dotted line in Fig. 3. The grooves 6 and 7 communicate at their inner ends with the longitudinal groove 4 and terminate at their 110

outer ends a short distance from the longitudinal edges of the stave, thereby leaving outer portions of the edges 2 and 3 flat. One longitudinal edge of the stave is formed 5 with a half round groove 8 whereas the opposite longitudinal edge is made convex, as indicated at 9. The concave and convex longitudinal edges 8 and 9 of the stave are of corresponding outline so as to match and 10 extend transversely the full thickness of the stave, as indicated most clearly in Fig. 4. The opposite end of the stave is formed with transverse offset edge portions 10 and 11, and an intermediate longitudinal portion or 15 shoulder 12. The edge portions 10 and 11 and the longitudinal shoulder 12 are formed with projecting convex portions 13, 14 and 15 to match the corresponding grooves 6, 7 and 5 at the opposite end of the stave with 20 the result that when a number of staves are placed together with their ends in contact the projecting convex portions 13, 14 and 15 of one stave enter the grooves 6, 7 and 5 in 25 the end of the adjacent stave, thereby forming an interlocking joint to hold the staves in alignment against lateral displacement. The outer portions of the edges 10 and 11 beyond the projecting convex portions 13 and 14 are made flat so as to abut against 30 corresponding flat portions of the edges 2 and 3 of the adjacent stave, thereby preventing undue strain upon the thin edges at the sides of the grooves 6 and 7.

It is to be understood that the staves intended to form the top and bottom courses have their outer edges straight, as indicated 35 most clearly in Fig. 1. It is also contemplated to provide a number of staves of about half the length of the general stave 40 and these short staves are designed for the top and bottom courses and are arranged to alternate with the usual staves so as to break joints, as indicated most clearly in Fig. 1. A structure embodying the invention 45 has the abutting edge portions of adjacent staves interlocked by reason of the concave and convex matching edges. The matching and abutting ends of the staves of adjacent courses have overlapping end 50 portions, as indicated most clearly in Fig. 1 and these overlapping end portions are engaged by means of the hoops, bands or binders 16 by means of which the structure is held from outward displacement. Besides 55 overlapping and having the overlapping portions engaged by the hoop or binder 16, the staves also interlock by reason of the matching concave and convex edge portions. The flat edge portions beyond the grooves 60 and projecting convex edge portions abut and sustain the major part of the weight, thereby preventing injury to the thin walls along the sides of the grooves 6, 7 and 5. One side of each stave is flat, as indicated 65 at 17 whereas the opposite side may be con-

vex, as indicated at 18, to conform approximately to the circular outline of a silo or like structure.

In the formation of the slabs or staves the concave and convex edge portions vary 70 slightly to admit of a limited play to allow for expansion and contraction of the material and also to permit staves of standard size to be advantageously utilized in the formation of silos or like structures of different diameters. In the formation of a silo or like structure the staves of the first course are placed on end with short staves alternating with the long staves. The staves of the remaining courses are of the usual length 80 and are placed upon the staves of the preceding courses, thereby forming break joints. The several courses are made secure by hoops, bands or binders 16 which engage overlapping end portions of the staves of 85 adjacent courses. The top course of the silo or structure comprises long and short staves having an alternate disposition with the result that the upper end of the silo is level. The roof may be of any construction and 90 usually consists of slabs or staves of tapering form and arranged about as indicated in Fig. 1 to form a tight closure.

Having thus described the invention, what is claimed as new is:—

1. A structure embodying staves, each having end portions formed with terminal faces in different transverse planes separated by an intermediate longitudinal shoulder, the end faces and shoulder at one end 100 of each stave being formed with a tongue terminating at its ends short of the longitudinal edges of the staves, the end faces and shoulder at the opposite end of each stave, being formed with a groove adapted 105 to receive the corresponding tongue of an adjacent stave, said staves being arranged in vertical courses and arranged to break joint, and a binder encircling the structure and bearing against the staves.

2. A structure embodying staves arranged in courses, the staves of one course breaking joint with staves of adjacent courses, the abutting ends of staves of each course being formed with edge portions in different 115 transverse planes separated by a longitudinal shoulder, whereby vertical stresses upon the staves will be met and resisted by the transverse edge portions, and the abutting ends and shoulders of the staves of the 120 courses being formed with interlocking means preventing lateral movement of one stave with respect to the other in all directions.

3. A stave having longitudinal edges, one longitudinal edge being formed throughout 125 its length with a tongue and the other longitudinal edge being formed throughout its length with a groove adapted to receive the tongue of a corresponding stave, each end of the stave being formed with faces in 130

- spaced transverse planes separated by an intermediate longitudinal shoulder, the shoulder and end faces, at one end of the stave, being formed with a groove terminating 5 short of the longitudinal edges of the stave and the shoulder and end faces at the opposite end of the stave being formed with a tongue terminating short of the longitudinal edges of the stave and adapted to seat 10 in the groove of a corresponding stave, whereby when two staves are engaged end to end the longitudinal shoulders will interlock and the tongue and groove formed at the abutting ends of the staves will interlock 15 and hold the staves against independent lateral movement in all directions.
4. A stave for silo construction made up of a plurality of duplicate sections arranged in endwise relation, each section being of 20 approximately uniform width and thickness and having the ends thereof presenting projections oppositely disposed with respect to the longitudinal median line of the section to present abrupt shoulders longitudinally 25 of the section, the respective sections being arranged in opposing relation with respect to their projections to provide an interfit locking edge section against independent lateral movement with respect to 30 the endwise adjacent sections, each section being formed substantially throughout its edge outline for interlocking fit with endwise adjacent sections and with lateral adjacent sections of the immediately adjacent staves.
5. A stave having opposite end portions, each formed with terminal faces in different transverse planes separated by an intermediate longitudinal shoulder, the end faces 35
- and shoulder at one end of the stave being 40 formed with a tongue and the end faces and shoulder at the opposite end of the stave being formed with a groove adapted to receive the corresponding tongue of another 45 stave.
6. A stave having opposite end portions, each formed with terminal faces in different transverse planes separated by an intermediate shoulder, the end faces and shoulder at one end of the stave being 50 formed with a tongue and the end faces and shoulder at the opposite end of the stave being formed with a corresponding groove, and a diagonally disposed reinforcing bar embedded in the stave and having one end 55 thereof disposed near the upper terminal face at one end of the stave and its other end disposed near the lower terminal face at the opposite end of said stave.
7. A structure embodying molded staves 60 arranged in courses, the staves of one course breaking joint with the staves of an adjacent course and the abutting ends of adjacent staves being formed with terminal faces in different transverse planes separated by 65 a longitudinal shoulder, the terminal faces and shoulder at one end of each stave being formed with a tongue and the terminal faces and shoulder at the opposite end of each stave being formed with a groove adapted 70 to receive the corresponding tongue of an adjacent stave, binders engaging the abutting ends of adjacent staves, and diagonally extending stays embedded in the staves with their ends projecting into the portions of 75 the staves engaged by the binders.

In testimony whereof I affix my signature.

WARREN A. CALDWELL. [L. s.]
